UNITED STATES PATENT OFFICE.

CORNELIUS DIELEMAN, WIEGERT D. RIETVELD, AND JOHN D. RIETVELD, OF PELLA, IOWA.

MANURE-LOADER.

No. 928,187.

Specification of Letters Patent. Patented July 13, 1909.

Application filed August 10, 1908. Serial No. 447,899.

To all whom it may concern:

Be it known that we, CORNELIUS DIELEMAN, WIEGERT D. RIETVELD, and JOHN D. RIETVELD, citizens of the United States, residing at Pella, in the county of Marion and State of Iowa, have invented a certain new and useful Manure-Loader, of which the following is a specification.

The object of our invention is to provide a manure loader of simple, durable and inexpensive construction, of the class having a receiving platform designed to receive a quantity of manure from a scraper or the like, and so arranged that when the platform is full, it may be elevated to position for discharging in a wagon.

More specifically it is our object to provide improved means for elevating the platform, whereby a minimum of applied power is necessary, and whereby the platform will start on its upward movement slowly, and its speed will be increased as it approaches the dumping point, so that the load upon the draft animal will be substantially equalized throughout the entire movement of the platform.

Our invention consists in certain details in the construction, arrangement and combination of the various parts of the device, whereby the objects contemplated are attained, as hereinafter more fully set forth, pointed out in our claims and illustrated in the accompanying drawings, in which—

Figure 1 shows a side elevation of the complete device embodying our invention. The dotted lines in said figure show the platform in its elevated position ready to discharge, and Fig. 2 shows a rear end elevation of the device embodying our invention. The dotted lines in said figure show the platform in its elevated position.

Referring to the accompanying drawings, we have used the reference numeral 10 to indicate the base sills, of which there are four, and which serve as runners to support the device when being transported from place to place. Mounted upon the runners 10 is a frame, composed of four stationary uprights 11 adjacent to the rear of the runners and supported in an upright position by means of the brace beams 12 which are

connected to the forward end of the runners. Fixed to the forward ends of the runners is a frame comprising the uprights 13 and braces 14. This frame is designed to support two rollers 15 a suitable distance above the forward ends of the runners. Mounted in the upper ends of the rear uprights 11 is a rotatable shaft 16. Fixed to the central portion of this shaft is a large gear wheel 17, and fixed to the end portions of the shaft are the tapered drums 18. Below the central portion of the gear wheel 17 is the shaft 19 having a small gear wheel 20 fixed thereto and in mesh with the gear wheel 17, and also having a drum 21 thereon adjacent to the small gear wheel. Above the rear ends of the runners is a rail 22 having a pulley 23 connected therewith. A rope or cable 24 is fixed to and wound upon the drum 21, and it is then passed through the pulley 23, and it is intended that a draft animal be attached to the other end of the rope. Fixed to and wound upon the drums 18 are the chains 25, which chains are passed over the rollers 15, and the forward ends are attached to the platform, as will hereinafter appear.

Pivoted to the rear ends of the outer runners 10 are the arms 26 which extend forwardly beyond the runners and which support the platform 27 at their forward ends. Said platform lies wholly in front of the sills. Fixed to the rear edge of the platform is an auxiliary platform 28 extended upwardly and rearwardly from the platform 27, and secured in said position by means of the braces 29. When the chains 25 are wound upon the drums 18, the arms 26 and the platforms connected with them will be elevated to a substantially vertical position. In order to limit the rearward movement of the arms we have attached the brackets 30 to the uprights 11.

In order to cushion the rearward movement of the platform, and also to start the platform on its return movement after discharging its load, we have provided the following mechanism. Pivoted to the two central uprights 11 are the arms 31 extended downwardly and forwardly and resting upon the support 32. These arms have a box 33 fixed to them to contain a weight.

One or more chains 34 are attached to the arms 31 and also to the platform 27, said chains being of such length that when the platform approaches a vertical position, the 5 arms 31 and the box 33 thereon will be elevated, as shown by dotted lines in Fig. 1, and obviously the weight on said arms will tend to return the platform to starting position after the load is discharged. It is only 10 necessary that the manure platform be started on its return movement, because after it has reached a certain point in its movement, it will return the rest of the way by gravity.

In practical use, the platform 27 is first 15 filled with the material to be loaded, and the platform is of such shape that a scraper full of manure or other material may be easily run on it and dumped. When the platform is full, the draft animals attached to the 20 scraper 24 are advanced. This will cause the drum 21 to rotate and this in turn will rotate the shaft 16, on which the drums 18 are mounted. The gearing device between 25 said shafts gives an increased leverage so that the weight of the platform and its load may be easily elevated by the draft animals. By having the chains 25 wound upon tapered drums, we obtain a considerable advantage 30 in that when the platform starts from its horizontal position upwardly, the chains wind upon the small part of the drum, and hence the platform moves relatively slow, and then as the elevation of the platform increases and it becomes easier to move 35 throughout the rest of its path, the chains wind upon the larger portion of the drum, and hence the platform moves farther. In this way the weight or strain upon the draft animals attached to the rope 24 is made sub- 40 stantially uniform throughout the entire movement of the platform. Furthermore, by having the rollers 15 arranged above the point where the chains are attached to the platform, the chains have almost a direct 45 upward pull upon the platform during the initial part of its movement.

We claim as our invention:—

1. In a device of the class described, the 50 combination of a frame, uprights at the rear of the frame, arms pivoted to the frame and extended forwardly, a platform on said arms, a shaft mounted in the uprights at the rear of the frame, a drum fixed to the same shaft, a cable fixed to and wound upon the drum, a small gear wheel on the shaft, a second shaft adjacent to the first, a large gear wheel on it in mesh with the small gear wheel, drums on the second shaft, and chains fixed to and wound upon 55 said drum and extended forwardly and attached to the platform.

2. In a device of the class described, the 60 combination of a frame, uprights at the rear of the frame, arms pivoted to the frame

and extended forwardly, a platform on said arms, a shaft mounted in the uprights at the rear of the frame, a drum fixed to the same shaft, a cable fixed to and wound upon the drum, a small gear wheel on the shaft, a second shaft adjacent to the first, a large gear wheel on it in mesh with the small gear wheel, drums on the second shaft, and chains fixed to and wound upon said drum and extended forwardly and attached to the platform, said drums being tapered and 70 so arranged that the chains will wind upon the small part of the drums during the initial upward movement of the platform and will then wind upon the larger part of the drum as the platform is being elevated. 80

3. In a device of the class described, the combination of a frame, uprights at the rear of the frame, arms pivoted to the frame and extended forwardly, a platform on said arms, a shaft mounted in the uprights at 85 the rear of the frame, a drum fixed to the same shaft, a cable fixed to and wound upon the drum, a small gear wheel on the shaft, a second shaft adjacent to the first, a large gear wheel on it in mesh with the small gear 90 wheel, drums on the second shaft, chains fixed to and wound upon said drum and extended forwardly and attached to the platform, said drums being tapered and so arranged that the chains will wind upon the 95 small part of the drum during the initial upward movement of the platform and will then wind upon the larger part of the drum as the platform is being elevated, uprights at the forward end of the frame, and rollers 100 on said uprights to engage said chains in such a manner as to give a substantially direct upward pull upon the platform at the initial portion of the platform movement.

4. In a device of the class described, the 105 combination of a frame, uprights at the rear of the frame, arms pivoted to the frame and extended forwardly, a platform on said arms, a shaft mounted in the uprights at the rear of the frame, a drum fixed to the same shaft, a cable fixed to and wound upon the drum, a small gear wheel on the shaft, a second shaft adjacent to the first, a large gear wheel on it in mesh with the small gear wheel, drums on the second shaft, 115 chains fixed to and wound upon said drum and extended forwardly and attached to the platform, said drums being tapered and so arranged that the chains will wind upon the small part of the drum during the initial 120 upward movement of the platform and will then wind upon the larger part of the drum as the platform is being elevated, uprights at the forward end of the frame, rollers on said uprights to engage said chains in such 125 a manner as to give a substantially direct upward pull upon the platform at the initial portion of the platform movement, weighted

arms pivoted to the rear uprights and extended downwardly and forwardly, and chains fixed to said arms and also to the platform and of such length that the weighted arms will be elevated as the platform approaches its rearward limit of movement, and an auxiliary platform at the rear of the main platform, inclined upwardly and rearwardly therefrom, and means for limiting

the rearward movement of the platform 10 arms.
